UNITED STATES PATENT OFFICE.

SAMUEL T. SHROYER, OF BELLEFONTAINE, OHIO.

SAFETY-CHECK FOR AUTOMATIC COUPLINGS.

No. 922,348.

Specification of Letters Patent.

Patented May 18, 1909.

Application filed November 30, 1908. Serial No. 465,463.

To all whom it may concern:

Be it known that I, SAMUEL T. SHROYER, a citizen of the United States, residing at Bellefontaine, in the county of Logan and 5 State of Ohio, have invented a new and useful Improvement for Safety-Checks for Automatic Couplers, of which the following is a specification.

My invention relates to certain improvements in automatic car couplers, especially 10 those known as the knuckle type, and consists in providing a safety device to prevent draw heads from dropping on the track when pulled out of the car frame.

15 Figure 1 is a top view of a set of draw heads with the knuckles locked in position. Fig. 2 is a detached, perspective view of one of the knuckles of the coupler now in general use, showing the ribs or my addition to the 20 knuckles.

The object of my invention is to provide a means of automatically preventing draw heads of cars from falling on the track when pulled out of the car frame.

25 Automatic couplers are of many different types, but most of them belong to what is known as the knuckle class, very similar to the one shown in the drawing, in which the two knuckles A A lock together as shown in 30 Fig. 1. Wrecks are of daily occurrence on most of the roads of the country caused by the drawbar, from some cause or another, being pulled out of the car frame, falling on the track and derailing and smashing part or 35 all the cars following. The knuckle form of coupler is efficient and reliable in a straight pull, but heretofore there has been no provision made to prevent the loose drawbar, which had pulled out of the car frame from

dropping to the track in the path of the approaching cars to the rear. These drawbars, weighing several hundred pounds each, dropped on the track in front of an approaching car are too large to pass beneath the cars and results in derailing the cars following. 45 To prevent the serious consequences of the drawhead falling on the track when pulled out, I form two ribs, or projecting ledges B, C, on the inside of each knuckle A, one at the top of the knuckle and the other at B, about 50 midway of its perpendicular face.

When the cars are coupled and the knuckles locked in position shown in Fig. 1, the lower rib or projection B of each knuckle is in line directly below the projection C on 55 the other knuckle so that, if from any cause, one of the drawbars should pull out of the car, the knuckle instead of falling with the drawhead to the ground, is arrested by the projection C dropping onto the rib or shelf 60 B, where it is held firmly, the two knuckles holding securely in each other's grasp, with the one on the detached draw bar slightly 65 lower than the other, but held from falling on the track.

What I claim is:

The combination with the knuckle clutches in an automatic car coupler of projecting lugs C at the top of each of the knuckles, and the ledges B on each of the knuckles, the ledge 70 B on each knuckle being situate beneath the lug C on the opposite knuckle when the knuckles are interlocked, as and for the purpose set forth.

SAMUEL T. SHROYER.
